THEODORE C. ROBERTS, OF NEW YORK, N. Y., ASSIGNOR, BY MESNE ASSIGNMENTS, TO COLUMBIA PHONOGRAPH COMPANY, INC., A CORPORATION OF NEW YORK.

SPRING MOTOR.

Original application filed May 5, 1921, Serial No. 467,113. Divided and this application filed December 16, 1922. Serial No. 607,377.

To all whom it may concern:

Be it known that I, THEODORE C. ROBERTS, a citizen of the United States, and a resident of the city of New York, county and State of New York, have invented certain new and useful Improvements in Spring Motors, of which the following, taken in connection with the accompanying drawings, is a specification.

10 This invention relates to improvements in spring motors, this application being a division of application, Serial No. 467,113, filed May 5, 1921. While such improvements are capable of more or less general use, the present embodiment has been particularly conceived with reference to phonographic use, which requires certain features and refinements which may be desirable in other uses, but are not always essential. It will, therefore, be understood that in describing the invention adapted to such use, that all other uses to which it may be put are comprehended.

An object is the provision of an improved spring and spring barrel construction adapted to greatly simplify the assembly or disassembly of the motor, without the use of special tools and parts, and in which the possibility of spring breakage is reduced to a minimum. In particular, the springs, as here shown, are adapted to hook themselves into place automatically, should they become unhooked, and also this feature is utilized in the original assembly of the motor,—no attempt being made to hook them before the motor is first wound, the winding automatically causing the springs to hook at their ends. Further, irregular strains on the springs are absorbed by the peculiar form of flexible connection of the springs with the spring barrels.

The structure also has for its purpose the provision of easy winding and a more uniform transmission of power.

45 With the above and other objects in view, embodiments of this invention are shown in the accompanying drawings, and these embodiments will be hereinafter more fully described with reference thereto, and the invention will be finally pointed out in claims.

In the accompanying drawings—

Fig. 1 is a vertical sectional view through the spring mounting portion of a motor,

showing the present invention incorporated therein;

Fig. 2 is a perspective view of one end of a spring barrel, showing the closure head in place thereon;

Fig. 3 is a vertical transverse sectional view of the spring barrel; and

Fig. 4 is a perspective view, showing both ends of one of the power springs.

Fig. 5 is a detail sectional view on the line 5—5 of Fig. 1.

Fig. 6 is a perspective view of the closure head and the spring-holding wires.

Fig. 7 is a detail sectional view on the line 7—7 of Fig. 2.

Similar reference characters indicate corresponding parts throughout the several figures of the drawings.

The horizontal spring-supporting shaft 40, upon which the spring elements are mounted, is non-rotatably supported at its ends in bushings 41 and 42 provided in the depending side portions 25 and 26 of the frame; the bushing 41 being shouldered interiorly, the greater diameter portion, inwardly of the shoulder, being unthreaded and engaged by the shaft, while the remaining portion is screw-threaded and engaged by the threaded reduced end 43 of the shaft, the projecting extremity of which is engaged by a nut 44. The bushing 41 is threaded exteriorly at its ends and is engaged by nuts 45 and 152 bearing upon each side of the frame portion 25. The bushing 42 is provided with a plain bore and exteriorly it is threaded at its ends and engaged by nuts 46 and 47 bearing upon the sides of the frame.

The shaft 40 extends beyond the bushing 42 and is shouldered, as at 48, to provide an abutment for the pawl 49, held in place by a washer 50 and a nut 51 screwed upon the reduced threaded extremity 52 of the shaft.

In the present embodiment there is illustrated a two-spring motor, the two springs 53 and 54 being housed in a single spring barrel 55 freely rotatable about sleeves 56 and 57 rotatable upon the shaft 40, the springs being connected at their inner ends to the sleeves, and at their outer ends to the barrel. The sleeve 56 has a gear 58 mounted upon its end and meshing with a pinion 59 journaled upon the frame, the pinion 59

being in turn, meshed by a pinion 61 provided upon the inner end of the winding shaft 62 journaled in the frame.

A ratchet 64 is provided upon the winding shaft and cooperates with the silent pawl mechanism, indicated generally as 49, and which permits silent winding and prevents reverse movement of the shaft.

The springs 53 and 54 are wound in opposite directions and act part of the time to counteract each other. In the present instance, the sleeve 56 is rotated in a clockwise direction upon the proper manipulation of the winding crank. This sleeve carries with it the inner end of the spring 54. Upon the spring being wound to a certain extent, the tension thereof reaches a point where the casing is carried with the spring.

As the casing revolves, the outer end of the spring 53 is carried in a clockwise direction, and the inner end of the spring, due to the fact that it is secured to the sleeve 57, remains stationary. Sleeve 57 is held stationary through the medium of a brake applied to the turntable or to the governor, or some other part of the motor acting through gearing.

The sleeve 57 has connected to its outer end a large worm gear 72, actuated by the unwinding of the springs, to drive the turntable shaft through intermediate gearing (not shown).

Upon the springs 53 and 54 being wound in the manner above pointed out, the outer end of the spring 54 will tend to move in a clockwise direction and the outer end of spring 53 will tend to move in a counter-clockwise direction. The inner ends of the springs are maintained stationary through the medium of the pawl and ratchet mechanism and the brake means, respectively.

The outer ends of the springs being connected to a single integral member, and tending to move in opposite directions, counteract each other, and thus the casing remains stationary. However, upon the brake being released, the spring 53 begins to unwind from its inner end and drives the gear 72 which, in a well-known manner, drives the turntable through the medium of intermediate gearing.

The spring barrel 55, housing the springs 53 and 54, is cup-shaped, and at its open end is provided with a removable closure head 73 (Fig. 6) adapted to be held in place by spring-holding wires 74 and 75, clipped thereto by diametrically opposed overturned lugs 76 and 77 (Figs. 6 and 7), and engaging an annular groove 78 formed at the open end of the barrel. The closure head 73 is a disc and the lugs 76 and 77 are formed at diametrically opposite points on the edge of the disc. To form the lugs, spaced cuts are made in the disc at its edge and the material between the cuts rolled into

the desired shape. At diametrically opposite sides of the barrel the annular grooved portion 78 is provided with elongated slots 162 and 163, which are engaged by the outwardly bent ends 164 of the springs. The elongation of the slots relatively to the combined width of the ends facilitates insertion of the ends and also permits of considerable tolerances of dimensions, which are of considerable manufacturing advantage. When not in position holding the head 73, the wires 74 and 75 spring toward a straight position, and may in fact be substantially straight in their disengaged untensioned position. This structure is such as to fix the position of the head to prevent its displacement either inwardly or outwardly, and the joint formed by the engagement of the springs with the groove will prevent the leakage of the lubricant provided in the barrel, and at the same time, the head may be removed by merely inserting a screwdriver, or the like, underneath the springs to release them from the groove.

The motor springs 53 and 54, as shown in Figs. 3 and 4, are provided at their inner ends with V-shaped hooks 79, and at their outer ends with bayonet slots 80, the teeth of the respective springs adapted to engage the longitudinal slots 81 and 82 formed in the sleeves 56 and 57, while the bayonet slots are engaged by buttons 83 and 84 secured to the barrel. A spring-separating disc plate 85, having its center hole 86 engaging the joint between the sleeves, is disposed between the springs, the sleeves being beveled at their adjacent ends,—as at 155 and 156,—thereby forming an annular channel in which the disc plate 85 has its bearing, and which maintains the disc plate in a normal plane of rotation and prevents its longitudinal displacement. Slightly convex bevels 157 and 158 are formed interiorly at the adjacent ends of the sleeves, so that there is substantially line contact between the ends of the sleeves, thus permitting a limited amount of lubricant to flow between the shaft 40 and the sleeves without clogging.

The spring structure is such that if the springs become unhooked they will hook again automatically, and in fact they are initially assembled without attempting to hook them. The V-shaped hook 79 at the inner end of the springs will prevent the production of any irregular strains, such as might be produced when rivets are used, and tight winding of the spring will only tend to hold it tighter.

While there is illustrated and described preferred and satisfactory embodiments of this invention, it is obvious that changes may be made therein which come within the spirit and scope of the appended claims.

Having now described the invention, what is claimed as new, and for which

Letters Patent of the United States is desired, is:

1. In a motor, a spring arbor, a spring barrel rotatably mounted upon the arbor, a coil spring disposed in the barrel and connected at its ends to the arbor and barrel respectively, a closure head disposed in one end of the barrel, and spring means connected to the head and adapted to yieldably retain the head in the barrel. 65
2. In a motor, a spring arbor, a spring barrel rotatably mounted upon the arbor, a coil spring disposed in the barrel and connected at its ends to the arbor and barrel respectively, a closure head disposed in one end of the barrel, and circumferential spring means connected to the head, adapted to engage the inner periphery of the barrel, to yieldably retain the head in the barrel. 70
3. In a motor, a spring arbor, a spring barrel rotatably mounted upon the arbor, a coil spring disposed in the barrel and connected at its ends to the arbor and barrel respectively, a closure head disposed in one end of the barrel, and a plurality of spring wires connected at spaced points to the head, and engaging the inner periphery of the barrel, to yieldably retain the head in the barrel. 75
4. In a motor, a spring arbor, a spring barrel rotatably mounted upon the arbor, and provided adjacent one end with an annular groove, a closure head disposed in such end of the barrel, and circumferential spring means connected to the head adapted to engage said annular groove, to yieldably retain the head in the barrel. 80
5. In a motor, a spring arbor, a spring barrel rotatably mounted upon the arbor, a closure head disposed in one end of the barrel, a pair of wire spring members secured near the edge of the head at diametrically opposite points, and bent into circumferential form to engage the inner periphery of the barrel, to yieldably retain the head in place. 85
6. In a motor, a spring arbor, a spring barrel rotatably mounted upon the arbor, a closure head disposed in one end of the barrel, circumferential spring means engaging the inner periphery of the barrel to retain the head in place, and a clamping lug formed upon the head to secure the spring means thereto. 90
7. In a motor, a spring arbor, a spring barrel rotatably mounted upon the arbor, a closure head disposed at one end of the barrel, a plurality of spring wires bent into circumferential relation to engage the inner periphery of the barrel, respectively forming segments of a circle, and means connecting the respective wires at spaced points to the head. 95
8. In a motor, a spring arbor, a spring barrel rotatably mounted upon the arbor, a closure head disposed in one end of the barrel, a plurality of spring wires bent into circumferential relation to engage the inner periphery of the barrel, respectively forming segments of a circle, and clamping lugs formed upon the head adapted to connect the respective wires thereto at spaced points. 100
9. In a motor, a spring arbor, a spring barrel, a coil spring disposed in the barrel and connected at its ends to the arbor and barrel respectively, a closure head disposed in one end of the barrel, circumferential spring means having free end-portions connected to the head intermediate such ends, and engaging the inner periphery of the barrel to yieldably retain the head in the barrel, and means removably fixing the ends of the spring means in the barrel. 105
10. In a motor, a spring arbor, a spring barrel having slotted portions adjacent one end, a coil spring disposed in the barrel and connected at its ends to the arbor and barrel respectively, a closure head disposed in one end of the barrel, a plurality of spring wires connected at spaced points to the head, and engaging the inner periphery of the barrel to yieldably retain the head in the barrel, and outwardly bent lugs at the ends of the spring wires, and engaging the slotted portions of the barrel to removably fix the ends of the springs. 110
11. In a motor, a spring arbor, a spring barrel rotatably mounted upon the arbor and having a pair of diametrically opposed slots adjacent one end, a closure head disposed in such end of the barrel, a pair of wire spring members secured near the edge of the head at diametrically opposite points, and bent into circumferential form engaging the inner periphery of the barrel to yieldably retain the head in place, the ends of the respective spring wires being adjacent and bent outwardly and disposed in said slots, to removably fix the springs. 115
12. In a motor, a spring arbor, a spring barrel rotatably mounted upon the arbor and having a pair of diametrically opposed slots adjacent one end, a closure head disposed in such end of the barrel, a pair of wire spring members secured near the edge of the head at diametrically opposite points, and bent into circumferential form engaging the inner periphery of the barrel, to yieldably retain the head in place, the ends of the respective spring wires being adjacent and bent outwardly and disposed in said slots, to removably fix the springs, the slots being elongated relatively to the ends of the springs. 120

Signed at New York, in the county of New York and State of New York, this 12th day of December A. D. 1922.

THEODORE C. ROBERTS,
